UNITED STATES PATENT OFFICE

OSKAR WALDRICH, OF SIEGEN, GERMANY

COPYING MECHANISM

Application filed July 1, 1931, Serial No. 548,070, and in Germany July 30, 1930.

This invention relates to copying mechanism and more particularly to a copying lathe adapted to operate on a polygonal work-piece, for example a four cornered work-piece.

The general object of the present invention is to provide a construction of copying lathe of such a nature that the shaping of the cross-sectional contour of a work-piece is not effected under the control of a template mounted behind the bed of the machine so as to extend throughout the length of the work-piece and adapted to move or actuate a tool supporting structure.

15 In accordance with the present invention the shaping of the work-piece is effected under the control of a cam which imparts an oscillatory motion to the upper tool supporting slide about a pivot located below the 20 work-piece being operated on.

In the accompanying drawings one constructional form of lathe embodying the invention is diagrammatically illustrated by way of example, parts of the lathe not necessary for understanding the invention being omitted from the drawings.

Figure 1 is a side elevation of the machine partly in section.

Figure 2 is a side elevation.

30 Figure 3 is a plan view.

The bed 1 of the machine supports a bed slide 2 on which an intermediate slide 3 is movably mounted. A support 5 is oscillatably carried by a pivot 4. A rocker 6 is rotatably mounted at the point 7 on the bed slide 2. The free end of the rocker bears on a cam or eccentric 8 secured to a shaft 9.

When a four cornered work-piece is to be operated on, the shaft 9 is rotated with the eccentric 8 and this causes an oscillatory motion to be imparted to the pivotal support 5 by means of the rocker 6 and a transversely adjustable member 10. The shaft 9 is rotated at four times the speed of the work-piece so that the cutting tool approaches to and recedes from the axis of the work-piece four times during each rotation of the latter owing to the oscillatory motion of the support 5.

50 In order that work-pieces having edges of

differing lengths may be turned the support 5 must be able to execute a greater or smaller stroke as required. For this purpose the member 10 is transversely adjustable by means of a hand wheel 11 and spindle 12.

55 When the transversely adjustable member 10 is near to its extreme left hand position the stroke of the support 5 is a maximum and becomes smaller according as the member 10 approaches the pivot point 7.

60 When a circular work-piece is being operated on in the machine the transversely adjustable member 10 is traversed to the extreme right hand position so that the roller 13 carried thereby is no longer in contact with the rocker 6. The oscillatory motion of the support 5 is thus interrupted.

65 In order that a work-piece may be turned into conical shape a guide bar 14 is supported at the rear of the bed. By setting the guide bar 14 at an inclination corresponding to the inclination or conicity desired in the work-piece the intermediate slide 3 to which an arm 15 is firmly secured is moved backwards and forwards by means of a slide 16 guided 70 on the bar 14, so that the work-piece to be turned receives the desired conicity.

75 To this end the oscillatory motion of the support 5 must be greater at the thick end of the conically shaped work-piece than at the thinner end thereof. This is effected without difficulty since the intermediate slide 3 supports the adjustable member 10 through the medium of the support 5 so that the adjustable member participates in all the transverse displacements of the slide 3 and consequently the oscillatory motion is automatically reduced as the thickness of the work-piece is diminished.

80 In order to maintain the same cutting angle of the cutting tool during turning, the tool holder 18 is oscillatably supported in the upper support 19 movable on the oscillatory support 5.

85 The oscillatory motion of the tool holder 18 is also derived from the shaft 9. A gear wheel 20 mounted on the shaft 9 drives a gear wheel 21 firmly connected with a crank disc 22. An oscillatory motion is imparted 90 to the tool holder 18 from the crank disc 22.

by means of a connecting rod 23, an arm 24 and a quadrant 24' pivoted at 25 in order that the cutting angle of the tool may always be accurately adjusted.

5 The transverse displacement of the upper support 19 to suit different thicknesses of the work-piece is effected by means of a hand wheel and spindle as is the case with the transversely adjustable member 10.

10 By means of the lathe according to the present invention it is possible to produce by means of one and the same cam work-pieces having lateral surfaces which are either flat, convex or concave. By rendering the cam

15 disc inoperative it is further possible to turn a cylindrical work-piece.

By varying the number of revolutions of the shaping cam 8 in relation to the number of revolutions of the work-piece it is possible

20 to operate on a work-piece having any desired number of sides, the shape of the work-piece being determined by the contour of the shaping cam.

I claim:

25 1. A copying mechanism for turning a tapered polygonal work-piece, comprising a bed, a cutting tool mounted thereon, means for supporting a work-piece adjacent to said tool and for rotation on its longitudinal axis,

30 means for reciprocating said tool transversely of the axis of the work-piece, means for moving said tool axially of the work-piece, and means actuated by said axial movement of the tool for automatically changing the

35 starting points of its reciprocating strokes, and means governed by said last-mentioned means for automatically changing the lengths of said strokes.

2. A copying mechanism for turning a ta-
40 pered polygonal work-piece, comprising a bed, a slide mounted on the bed for longitudinal movement, a support disposed on the slide for transverse movement, a cutting tool mounted on the support, means for support-

45 ing a work-piece adjacent to said tool and for rotation on its longitudinal axis, means for oscillating said support to cause said tool to reciprocate transversely of the axis of the work-piece, means for moving said slide axi-
50 ally of the work-piece, means actuated by said axial movement of the slide for moving said support transversely thereof to automatically change the starting points of the reciprocating strokes of said tool, and means

55 associated with said support and oscillating means and governed by said last-mentioned means for automatically changing the lengths of said strokes.

3. A copying mechanism for turning a
60 tapered polygonal work-piece, comprising a bed, a slide mounted on the bed for longitudinal movement, a support disposed on the slide for transverse movement, a cutting tool mounted on the support, means for support-
65 ing a work-piece adjacent to said tool and for

rotation on its longitudinal axis, a lever pivoted to said bed and operatively engaging said support, means actuating said lever for oscillating said support to cause said tool to reciprocate transversely of the axis of the 70 work-piece, means for moving said slide axially of the work-piece, a guide bar mounted at the side of said bed in adjustable angular position, and means slidably secured to said bar and connected to said support for moving 75 the support transversely of said slide in accordance with the angular position of said bar as the slide moves longitudinally of the bed, said transverse movement of the support shifting the leverage between it and said oscillating means, whereby the lengths of the reciprocating strokes of said tool are automatically changed simultaneously with said transverse movement of the support.

In testimony whereof I affix my signature. 85
OSKAR WALDRICH.
